UNITED STATES PATENT OFFICE.

WALTER L. FAUST, OF NEWARK, NEW JERSEY, ASSIGNOR TO WHITLOCK CORDAGE COMPANY, OF JERSEY CITY, NEW JERSEY, A CORPORATION OF NEW JERSEY.

BULL ROPE.

Application filed March 15, 1923. Serial No. 625,375.

To all whom it may concern:

Be it known that I, WALTER L. FAUST, a citizen of the United States, and a resident of Newark, in the county of Essex and 5 State of New Jersey, have invented a new and Improved Bull Rope, of which the following is a full, clear, and exact description.

The present invention relates to new and 10 useful improvements in cordage and it pertains more particularly to that type of cordage known as "bull ropes." Due to the use to which "bull ropes" are put, great strength is not required. It is necessary, however, in 15 the manufacture of bull ropes that sufficient size or diameter be obtained.

In the manufacture of ropes generally, the product is formed of strands which strands in turn are composed of yarns and 20 said yarns in turn are composed of spun fiber. In manufacturing yarns, the fiber is subjected to various operations and machines, and at one step or another in the several operations, lubricant in the form of 25 specific oils, is applied to the fiber.

In carrying out the several operations by 30 which the fiber is converted into yarns, there is considerable waste separated from the fiber mass, in the form of short fibers, or- 35 ganic matter not removed by the original retting, and other foreign matter, which waste is separated from the fiber in order that the fiber may be in the most desirable condition for the manufacture of cordage. 40 This waste is known in the rope-making art as "rope mill waste."

As above stated, "rope mill waste" consists of short fibers, a comparatively large 45 percentage of the above-mentioned organic matter, and considerable foreign matter, the whole being practically saturated by the lubricant used in preparing the fiber for cordage operations, and this mill waste, so far as is known, prior to this invention, has had no commercial value.

Due to the character of this "rope mill 50 waste," it is of a flocculent nature, and it has been found by experiment that the degree of flocculence thereof is very high. It 55 has also been found by experiment that "rope mill waste" possesses a degree of compressibility especially desirable when used in this connection. It is, therefore, one of the primary objects of the present invention to

utilize this heretofore waste by-product in 55 the manufacture of cordage.

It is a further object of the invention to use this "rope mill waste" as a core for 60 rope structures, and such "rope mill waste," due to its flocculent nature, readily lends itself to use as a core for ropes wherein strength is not an important factor in the finished product.

While, as above stated, bull ropes are not required to carry great loads, they are in 65 use subjected to excessive friction and the oil with which the "rope mill waste" is practically saturated, lends itself as a lubricant for the finished product when the "rope mill waste" is used as the core of the strands 70 or of the rope itself in a bull rope.

As aforesaid, one of the requirements of the bull rope is size, and by employing "rope mill waste" as a core, due to the flocculent 75 nature of said material, it readily lends itself to cores of various diameters, thus giving the necessary bulk.

With the above and other objects in view, reference is had to the accompanying drawings, in which

Figure 1 is a view in elevation of a section of bull rope constructed in accordance with the present invention, one of the strands being partially unraveled;

Fig. 2 is a transverse sectional view taken 85 on the line 2—2 of Fig. 1.

In carrying out the invention, "rope mill waste" is formed into a core designated by the reference character 5 in the drawings, in any desired manner. After this has been 90 done, the core is provided with a protecting cover in the form of yarns 6, preferably spirally laid about the core, and this structure is known in the art as a "strand." After the strands have been formed of the 95 core 5 and yarns 6, a plurality of such strands are laid together to form the "bull rope," designated by the reference character 7 in the drawings.

From the foregoing it is apparent that the 100 present invention provides a new and improved rope structure, the manufacture of which permits of the use of a heretofore waste by-product which prior to this invention was possessed of no commercial value. 105

What is claimed is:

1. In a cordage element, a core comprising a mass of flocculent material.

2. A rope element comprising a core of flocculent material, said core having a covering of spirally laid yarns.
3. A rope element having a core formed of flocculent material, said flocculent material comprising "rope mill waste."
4. A bull rope comprising a plurality of elements in intertwined relation, said ele-
ments having a core of a flocculent mass, which flocculent mass comprising "rope mill waste" is impregnated with a lubricant.
5. A cordage element having a core of flocculent material possessed of a high degree of compressibility.

WALTER L. FAUST.
